UNITED STATES PATENT OFFICE.

ELBRIDGE T. LIKES, OF DES MOINES, IOWA.

TRACK-CLEANER.

SPECIFICATION forming part of Letters Patent No. 439,783, dated November 4, 1890.

Application filed May 22, 1890. Serial No. 352,703. (No model.)

To all whom it may concern:

Be it known that I, ELBRIDGE T. LIKES, of Des Moines, in the county of Polk and State of Iowa, have invented certain new and useful Improvements in Track-Cleaners; and I do hereby declare that the following is a full, clear, and exact description thereof, reference being had to the accompanying drawings, and to the letters of reference marked thereon, which form a part of this specification.

This invention relates to devices for cleaning railway-tracks; and it consists in the construction and combination of parts herein-after set forth, and pointed out in the appended claims.

Figure 1 is a side elevation of my improved track-cleaner applied to a car, parts being broken away to more clearly illustrate certain details of construction. Fig. 2 is a top view of the track-cleaning device and its actuating mechanism, the car-body being removed. Fig. 3 illustrates one of the revolving brushes in end view.

A represents the body or the truck-frame of a car provided with axles B, having wheels B', which run upon track-rails T.

C is a cross beam or bar at the front end of the car or truck frame, and D is a bar projecting forwardly from the middle of the cross-bar C, with which it is connected by a vertically-flexible joint, as, for example, shown at d.

E is a narrow plow secured to the front end of the bar D, and F is a rope or chain attached to the front end of said bar and intended to afford means by which the said bar and its attachments may be raised and lowered at will. For this purpose a device is shown consisting of a rotatable shaft G, to which the rope F is secured, said shaft being provided with a ratchet-wheel g, engaged by a detent-pawl g', and operated by a hand-lever G', having a pawl g'', the whole constituting a familiar form of ratchet-and-pawl mechanism for taking up and letting out a flexible connection like the rope F.

H H are two revolving brooms placed with their front ends behind the plow E and diverging at their rear ends to cross the track-rails T T. At their front ends said brooms are provided with journals h', which rotate in bearings formed or connected with braces e e,

that connect the outer ends of the plow E with the bar D, as more plainly indicated in Fig. 2. At their rear ends the brooms are connected by universal joints h'' with rotatable arbors I, mounted in bearings at the outer ends of arms I', which are secured to the car-body or to the cross bar or beam C, as the case may be. The joints h'' and d are in the same horizontal line to allow the brooms to be raised and lowered with the bar D. Back of and parallel with the cross-bar C is mounted a rotatable shaft J, having upon its ends the beveled gear-wheels j j, which mesh with corresponding wheels i i upon the rear ends of the arbors I. The shaft J is shown as being rotated by means of a sprocket-chain K, trained over a sprocket-wheel b, fixed on the axle B, and over a similar wheel j', loosely mounted upon the shaft J. The hub of the sprocket-wheel j' forms a clutch with the sliding member J' on the shaft J, so that the said shaft J may be rotated or not, at pleasure. Mechanism for sliding the clutch-sleeve J' is not shown, but may be of any suitable description of which many forms are well known. Other forms of gearing may of course be employed instead of the sprocket-gear illustrated.

From the foregoing description the operation of the device is obvious. The track-cleaner being located in front of the car when the latter is advanced, the shaft J is rotated through the medium of the gear connecting it with the axle, and rotative motion is given to the revolving brooms H H, throwing their lower surfaces outward and operating therefore to throw the snow or dirt beneath them outwardly from the track. The plow E serves to throw the snow when of considerable depth outwardly into the path of the brooms, and by the combined action of the plow and the brooms the tracks and the space between them is cleared.

By means of the ratchet-and-pawl mechanism G G' and rope or chain F the track-cleaning device may be raised and lowered to any desired distance from the track or to bring the brooms H H into bearing thereon with any desired degree of force.

It will be observed that the diverging ends of the plow E extend to the outermost portion of the front ends of the two brooms H H, so as to completely protect said ends and pre-

vent the snow or other obstacles on the track from contact with the ends of the brooms or the frame-braces *e e* and the journals *h'*.

I claim as my invention—

- 5 1. The combination, with a car provided with a plow, of a track-cleaner comprising rearwardly-diverging, rotating, and vertically-adjustable brooms, and gearing for rotating the brooms connecting the latter with the axle 10 of the car, the forward ends of said brooms being located in the rear of and protected by said plow, substantially as described.
2. The combination, with a car, of a vertically-flexible bar *D*, provided with a plow *E*, 15 at its outer extremity, revolving brooms *H H*,

diverging rearwardly from behind said plow, arbors *I I*, rotating in suitable bearings and flexibly joined with the rear ends of the brooms *H H*, a transverse shaft *J*, geared with the arbors *I I*, and a suitable gearing connecting the shaft *J* with the axle *B*, substantially as described. 20

In testimony that I claim the foregoing as my invention I affix my signature in presence of two witnesses.

ELBRIDGE T. LIKES.
